UNITED STATES PATENT OFFICE.

JAMES A. DOUGLAS, OF YATES LANDING, ILLINOIS.

ENVELOP.

No. 853,070.

Specification of Letters Patent.

Patented May 7, 1907.

Application filed May 5, 1906. Serial No. 315,366.

To all whom it may concern:

Be it known that I, JAMES A. DOUGLAS, a citizen of the United States of America, residing at Yates Landing, in the county of 5 Pulaski and State of Illinois, have invented new and useful Improvements in Envelops, of which the following is a specification.

This invention relates to improvements in mailing envelops, the object of the same being to provide a simple and inexpensive construction of envelop which cannot be tampered with for withdrawal of the contents thereof without detection.

In the accompanying drawings, Figure 1 is a rear view of an envelop embodying my invention as it appears when completely sealed. Fig. 2 is a similar view showing the partially sealed envelop as it appears before the insertion of the tongue. Fig. 3 is a plan 20 view of the envelop with parts outspread and with the inner sealing or protective sheet in position. Fig. 4 is a view similar to Fig. 3 with the body or the sealing sheet turned up to admit the letter sheet. Fig. 5 is a central 25 section through the sealed envelop.

The envelop may be of conventional form and any of the conventional sizes, and comprises in its main structure a body or front portion 1, rear bottom and end flaps 2 and 3 and a sealing flap 4. These flaps are gummed on their inner faces, as shown at 5, and the flap 2 is provided with a slit 6 for the passage of a tongue 7 formed upon the center of the flap 4, the said tongue being gummed on both 35 its inner and outer faces, the outer gummed portion being indicated at 7'. In conjunction with the envelop as thus formed, I provide an inner sealing or protective sheet 8 coextensive in size with the body 1 and 40 adapted to be inclosed with the letter sheet in the envelop. This sheet 8 is formed at its upper edge with securing tabs 9 turned over upon the front thereof and provided with gummed edges 10 to secure the same to 45 the back of the body or front 1.

In using the improved envelop, the tabs 9 are first secured to the body 1, the letter sheet applied against the body and tabs and the sheet 8 turned down over the back of the 50 letter sheet from the position shown in Fig. 4, after which the end flaps 3 are turned over upon and gummed to the back of the sheet 8, the bottom sealing flap 2 turned over upon and gummed to said end flaps, and the sealing flap 4 turned down and secured. In seal-

ing the flap 4 the inner gummed surfaces thereof are moistened to fasten the same to the flaps 2 and 3 and the inner face of the tongue 7 to the back of the sheet 8, and the outer gummed surface 7' of the tongue is also moistened to secure it to the inner surface of the flap 2, it being understood that after the gummed surfaces of the flap 4 are moistened the body of the flap is turned over upon the back of the envelop, the tongue 7 inserted 60 through the slit 6 and pressure exerted to cause the gummed surfaces to adhere to the parts they engage. It will thus be apparent that the letter sheet will be completely 65 inclosed and protected except at the ends of the envelop, and that the flaps cannot be unsealed by steaming or other processes or the ends of the envelop opened without giving 70 visual evidence of the fact that the envelop has been tampered with.

The ends flaps 3 are preferably of triangular form or otherwise so constructed that when folded and secured to the protective sheet their lower edges will be spaced sufficiently to allow the inner face of the tongue 7 75 to come in contact with a portion of the sheet. If desired, sealing wax or any other sealing medium may be applied to the flap 4 at its point of junction with the tongue 7, as, for instance, at 11, so that it may be secured to 80 the exposed rear portion of the protective sheet above the upper edges of the end flaps, thus obtaining additional security.

Having thus described the invention, what I claim is:

The herein described safety envelop comprising a body, a protective sheet substantially coextensive in size with the body, said sheet being secured at its upper edge to the body so as to be turned down upon the back 95 of the inclosure to confine the same between said sheet and the body, end flaps adapted to be gummed to the rear surface of the turned down protective sheet, said flaps being cut away at their lower edges to provide an intervening space through which a portion of the back of said sheet is exposed, a bottom flap gummed for attachment to the folded end flaps and provided with a central transverse slot adapted to register with the upper portion of said space, and a top sealing flap adapted to be turned down upon and secured to the end and bottom flaps, said sealing flap being formed with a central tongue for insertion through said slot to lie against the inner 105 110

surface of the bottom flap and against the exposed rear surface of the protective sheet between the spaced portions of the end flaps, said tongue being gummed on both sides for attachment to the portions of the bottom flaps and protective sheet against which it bears.

In testimony whereof, I affix my signature in presence of two witnesses.

JAMES A. DOUGLAS.
